UNITED STATES PATENT OFFICE.

JAMES H. STROUD, OF MABEL, MINNESOTA.

RAIN-ANNUNCIATOR.

1,109,481.

Specification of Letters Patent.

Patented Sept. 1, 1914.

Application filed December 29, 1913. Serial No. 809,359.

To all whom it may concern:

Be it known that I, JAMES H. STROUD, a citizen of the United States, residing at Mabel, in the county of Fillmore and State 5 of Minnesota, have invented certain new and useful Improvements in Rain-Annunciators; and I do hereby declare the following to be a full, clear, and exact description of the invention, such as will enable 10 others skilled in the art to which it appertains to make and use the same.

This invention relates to rain annunciators, and one of the principal objects of the invention is to provide an electrically operated device of simple construction which will ring an alarm bell when the first rain drop falls upon the device to complete a circuit through hygroscopic elements which bridged the terminals of the circuit.

20 Another object of the invention is to provide a small apparatus designed to be operated by small batteries for ringing a bell and announcing the fact that it is raining outside by completing a circuit through 25 connectors which bridged the terminals of the conductors.

These and other objects may be attained by means of the construction illustrated in the accompanying drawings, in which—

30 Figure 1 is a top plan view of the apparatus with the bell removed, Fig. 2 is a top plan view, showing the casing opened and portions in section, Fig. 3 is a top plan view of the interior support for the connectors, 35 Fig. 4 is a bottom plan view of the insulated cover, Fig. 5 is a section on an enlarged scale, taken on the line of 5—5 of Fig. 1, Fig. 6 is a similar view, taken on the line of 6—6 of Fig. 1, Fig. 7 is a longitudinal vertical sectional view.

Referring to the drawings, the numeral 1 designates a casing of sufficient size to contain a small dry battery 2. A supporting member 3 is fitted within the top of the 45 casing, and secured underneath the support 3 are the terminal connectors 4. Extending through the support 3 and connecting one end of each of the wires 4 is a binding screw 5—6. A spring contact 7 is connected to the binding screw 5 at one end, and the opposite end bears against a spring contact 8 connected to the battery 2. The binding screw 6 extends through the support 3 and connects a spring contact 9 with a similar contact 10 connected to the battery 2, said contact 9 bearing against a plate 11

secured to the crank arm 12 of an ordinary electric bell 13 provided with the usual casing 14.

Connections are made to the bell through 60 the wire *a* from the plate 11 to binding post *d* and through wire *a'* from the binding post *d'* to the binding post *d*.

The cover 15 for the casing is made of vulcanite, or other non-conducting material, 65 said cover having a rectangular recess extending through the same.

Extending across the recess in spaced relation are flat metal connectors 16—17 fitted in slots or grooves at opposite sides of the 70 rectangular recess in the cover 15. The connectors 16 and 17 are provided with spaced recesses 18—19 upon their lower edges, said recesses being formed in the alternate ends of the connectors, and secured in the said recesses are copper strips 19^a and 18^a bearing 75 upon the terminals 4.

Fitted between each pair of the members 16 and 17 is a hygroscopic element 20, which may be ordinary blotting paper, or other 80 similar material of a bibulous character.

The device is intended to be placed upon a window sill or in any other place exposed to the outer atmosphere, and when a rain drop falls upon the hygroscopic element 20, 85 a connection is made between the two members 16—17 through the moisture to the plates 18^a and 19^a and through the connections to the bell 13, and the latter will be operated until the device is taken in and the 90 current switched off by means of the crank 12.

Two or more of the covers 15 may be utilized so that they may be interchanged by securing a dry cover in place of one that 95 has been operated on by the moisture in the atmosphere.

This apparatus is simple in construction, is reliable in operation, is inexpensive to manufacture, and may be relied on for this 100 purpose.

Certain modifications may be made in the details of construction without departing from the spirit and scope of the invention as defined in the claims.

105 What is claimed is:—

1. A rain annunciator comprising a casing containing a battery, a support within the casing having spaced terminals connected thereto and spring contacts in connection 110 with the battery and an insulated cover provided with spaced connectors adapted to

bridge the terminals, and a hygroscopic element disposed within the spaces between the connectors.

2. A rain annunciator comprising a casing, batteries with the casing, a bell connected electrically to the batteries, a support, spring contacts carried by said supports and connected to the batteries, spaced terminals connected to said support, a non-conducting cover, provided with a series of spaced connectors, said connectors being alternately recessed on their lower edges, strips connected in said recesses, and their hygroscopic elements disposed between the connectors.
- 10 3. In an apparatus of the character de-

scribed the combination of a casing, batteries in said casing, a bell connected to the batteries, spaced terminals, and a top or cover for said casing made of a non-conducting material and provided with a recess extending through the same, spaced connectors extending across the recess and spaced apart, and hygroscopic elements disposed between the connectors. 20

In testimony whereof I affix my signature 25
in presence of two witnesses.

JAMES H. STROUD.
